UNITED STATES PATENT OFFICE

2,375,397

ROTARY PRINTING PRESS

William Arnold Whitehead, Preston, England, assignor to The Goss Printing Press Company, Chicago, Ill., a corporation of Illinois

Application May 30, 1942, Serial No. 445,113
In Great Britain July 28, 1941

5 Claims. (Cl. 101—350)

This invention relates to rotary printing presses and is more particularly concerned with such presses in which the ink is supplied to the distributing cylinders and forme rollers by means of pumps.

It is an object of this invention to arrange the box enclosing the ink pumps so that awkwardly projecting or extending parts which both impede the operator and obstruct the gangways of the pressroom may be eliminated or at least reduced by a substantial extent.

It is another object of this invention to provide a form of mechanical remote control for each individual pump located and arranged in a convenient position for the operator while being of simple construction and operation.

A further object of the invention is to provide novel and improved means for exposing the pump mechanism to view for the purpose of inspection, repair or replacement.

Other objects of the invention will be clear from the following description of an exemplary embodiment thereof as applied to a rotary printing press in which a single printing couple is designed to print a web of newspaper of a maximum width equivalent to four pages, each page having a maximum of eight columns of type.

In said drawings—

Figure 1 is an end elevation, partly in section, showing one of the press frame end members, the wheel guard and the ink pump box; and

Figure 2 is a side elevation, also partly in section, of Figure 1.

It is customary to enclose the gears of the ink distributing and forme rollers within a wheel guard secured to the press frame. With the foregoing objects in view and in accordance with the present invention, the ink pump mechanism is arranged in a box or casing attached to the press frame in line with the wheel guard in the vertical sense so that said box does not extend horizontally or to any substantial extent horizontally beyond the wheel guard. Each pump is provided with an adjustable controlling rod or screw extending upwardly from the pump box and projecting from the wheel guard casing at a readily accessible position, the rods lying within the area over which the wheel guard is situated. The wheel guard may be extended either directly or by means of one or more auxiliary plates to enclose said rods and to form a cover for the pump box. Such an arrangement enables the pump box and a distributing rail associated therewith to be moved as a unit relatively to the press frame in order to leave the mechanism readily

accessible for inspection, replacement or repairs and thus avoid the need for a removable cover for the pump.

Where the box is extended from beneath the wheel guard it may be formed with a panel to accommodate the several ink control or indicator devices usually provided with such presses. For example, the panel may accommodate a main ink supply cock, a float-controlled ink-level indicator and, where means are provided for controlling the supply of ink to a plurality of columns of newsprint, the controls therefor. Such means may consist of valve bars which are positioned to determine the quantity of ink supplied to the several columns of type for producing a single page of newsprint, each of the valve bars being operable by means of an eccentric on a rod or shaft projecting through the panel and having a manually actuatable knob on its upper end.

Referring now to the drawings, the press frame comprises end members 10, of which one is shown in the drawings and in which are journaled the impression cylinder 12, type cylinder 14, and a train of distributor and forme rollers or drums 16, 18, 20, 22, 24 and 26 by which ink is supplied to the type cylinder of the printing couple. The distributor and forme roller shafts are extended through the end press frame members and have secured thereto inter-engaging gears 28, 30, 32, 34, 36 and 38 by which they are driven from the main press drive, the type and impression cylinders being coupled through gears 40 and 42 to the gear 28. An oil bath 44 is provided near the base of each frame to provide for lubrication of the gears and each gear train is enclosed within a wheel guard 46 attached to the corresponding press frame member as by means of bolts 48.

Located adjacent the lower end of one of the press frame members is a box or casing 50 within which the ink pump mechanism is arranged and which serves as a reservoir for the ink. Secured immediately beneath the pump box is a rail 52 to the distributing face of which the ink is conveyed by means of a plurality of ports 54 of small bore, the ink being supplied to said ports by means of a plurality of pumps arranged within the pump box. In this embodiment there are thirty-two pumps, one for each of the columns of type matter, arranged in four rows with eight pumps in each row. The outlet ends of the ports 54 communicate with pipes 56 which convey the ink to the distributor roller 26 and the pipes are preferably spaced on the pump rail so that each

is located approximately centrally of the corresponding column of type.

The pump arrangement illustrated in the drawings is of a conventional type for use with printing presses and will therefore be described only in such detail as is necessary for a full understanding of the present invention. Arranged within the pump box 50 is a frame 58 having a plurality of apertures therethrough in which are guided a plurality of plungers 60, there being one plunger for each column of type. A coiled spring 62 is fitted about the upper end of each of the plungers and is compressed between the frame 58 and a collar 64 secured to the plunger. Upward movement of each plunger under the effect of its spring normally is limited by a further collar 66 secured to the plunger and abutting the lower face of the frame 58. The lower end of each of the plungers is located within a port or aperture in a frame 68 mounted in guideways 70 arranged within the base of the pump casing. Extending upwardly from the lower frame 68 are a pair of guide posts 72 which pass freely through correspondingly arranged apertures in the upper frame 58, the arrangement being such that the two frames are movable as a unit laterally of the machine while the upper frame is relatively vertically movable with respect to the lower frame.

Co-operating with grooves or channels 74 formed in the upper face of the frame 58 are a pair of eccentrics 76 to which rotation is imparted from the main press drive. For this purpose the spindle of the forme roller 24 is extended beyond the gear 36 to carry a worm 78 which meshes with a worm wheel 80 secured to a shaft 82 carried in bearings 84 in the wheel guard 46. The shaft 84 also has secured thereto a pinion 86 which meshes with an idler gear 88 in turn meshing with a pinion 90, the latter driving a pair of pinions 92 fixed on the shafts of the eccentrics 76. A hand controlled clutch is shown at 94 whereby the drive to the pumps may be disconnected without the need for stopping the press.

Rotation of the eccentrics through the mechanism described above causes the upper frame 58 to reciprocate laterally of the machine and, due to the posts 72, the lower frame 68 has imparted thereto a corresponding lateral movement within its guideways 70. This rotation of the eccentrics also effects a vertical movement of the frame 58 relative to the frame 68, which in turn produces an up-and-down movement of the plungers 60 within the apertures in the lower frame. During the upward or suction movement of the frame 58 and the plungers, the lower frame is moved to place the apertures in communication with ink channels 96 in the casing and during the downward movement the lower frame is returned to the position shown in the drawings so that the ink within the apertures in said frame is forced by the plungers through the ports 54 into the pipes 56, these alternate suction and discharge strokes of the plungers being continued under control of the clutch 94 to provide a constant supply of ink to the distributor drums and type cylinder.

To control the supply of ink from each individual pump, means are provided for varying the stroke of the plungers 60. Such means comprise a plurality of manually operable adjusting rods 98, one for each plunger, having heads 100 at their lower ends adapted to abut the upper ends of the plungers during the upward stroke of the latter. The rods are vertically carried in upper

and lower frames 102, 104 within the wheel guard 46 and at their upper ends project outside said guard through an opening 106 therein, being provided with knurled heads 108 by which they may be rotated. The heads 100 are in threaded engagement with the frame 104 so that upon rotation of the rods 98 the heads are vertically adjusted towards or away from the plungers. The knurled heads are preferably arranged at a convenient height to enable the operator to control the supply of ink from each pump without bending or stretching and the wheel guard forms an efficient closure for this mechanism.

In addition to the provision of means for controlling the supply of ink from each pump, there are also provided, for the purpose of controlling or cutting off the supply of ink to a row of pumps supplying one page of newsprint, a plurality of valve bars 110 which are arranged to slide in channels in the base of the pump casing. In the particular embodiment illustrated there are four such bars, and they are formed with apertures 112 therethrough by which the ink is fed from the pumps to the ports in the pump rail. The bars are movable in a horizontal plane at right-angles to the direction of oscillatory movement of the frame 68 and each has extending therefrom a horizontal rod 114 which is eccentrically connected at 116 to the lower end of a rotatable shaft 118 extending upwardly within the pump box. These shafts project through a panel 120 which covers a projecting portion of the pump box and this panel is of such dimensions as to accommodate a set of manually operable milled knobs 122 secured to the shafts 118, a float indicator pointer attached to the float 124 to indicate the level of ink in the reservoir and, preferably, a main ink supply cock.

The ink may be supplied to the reservoir through a pipe (not shown) coupled thereto and passing through a valve controlled by the supply cock, a filter and a valve 126 controlled by the float.

To provide access to the pump box 50 for inspection, repair or replacement, the box and the pump rail may be slid rearwardly (to the right in Figure 1) from beneath the wheel guard, thus leaving the upper face of the box uncovered. The pump plungers 60, in their mean position as shown in the drawings, will be seen to project upwardly within the wheel guard and when moving the latter it is necessary to ensure that said plungers do not strike against the heads 100 of the adjusting rods 98 which, to control the supply of ink to each individual pump as above described, are adjustable to varying heights. Before moving the pump box either inwardly or outwardly, therefore, the frame 58 and the plungers must be in substantially their lowermost positions so that the plungers will clear the press frame and, to ensure that the pump box cannot be moved far enough to damage the plungers until the latter are in this position, co-operable safety stop devices are provided within the wheel guard and on the pump frame. As here embodied, these safety devices comprise a fixed abutment 129 extending from the lower end frame 104 and a pair of spring-pressed pins 128 seated in the pump frame 58. These pins project upwardly from the frame 58 to a height such that one or other (depending on the direction of movement of the box) will engage the abutment 129 if said frame and therefore the plungers are not in the lowermost position, but will clear said

abutment when the pump frame and the plungers are in such position.

As will be clear from the drawings and from the foregoing description, the upper part of the ink pump box is mainly closed by the wheel guard 46 and that part of the box beneath the panel does not project from the press to an extent sufficient to impede the operator or obstruct the gangways of the press room. Further, the wheel guard encloses and conceals the pump adjusting rods from view. The extension of these rods to a convenient position on the exterior of the wheel guard casing provides, in effect, a form of mechanical remote control which is convenient and simple in operation.

What I claim and desire to secure by Letters Patent of the United States is:

1. Rotary printing press having a printing couple for printing a plurality of columns of type matter, means for conveying ink to the columns of type on the type cylinder, gearing for driving said ink-conveying means, pump mechanism for supplying ink to said ink-conveying means, a casing accommodating the pump mechanism and serving as a reservoir for the ink, a rail on said casing and means associated with said rail by which the ink is distributed on said ink-conveying means, and a guard for said gearing forming a closure for the pump casing, said casing and the rail being movable as a unit in the press frame relatively to the guard to expose the pump mechanism.

2. In a rotary printing press having a printing couple including a type cylinder for carrying a plurality of columns of type, means for conveying ink to each of said type columns, a plurality of pumps for supplying ink to said ink-conveying means, each of said pumps comprising a plunger working within a bore in a pump frame, a casing for accommodating said pumps, gearing for driving said ink-conveying means and for actuating said pump frame to impart suction and pressure strokes to said plungers, a guard for said gearing forming a closure for said pump casing, said casing being movable in the press frame to expose the pumps, a plurality of rods extending

within said guard and adjustably engageable with the plungers to limit their stroke and thereby control the supply of ink from the pumps, said rods having manually operable portions projecting from said guard, a fixed abutment within said guard, and projections on the pump frame engageable with said fixed abutment upon movement of the pump casing except when said pump frame is positioned to clear the guard.

10 3. In a rotary printing press having means for supplying and conveying ink to each of a plurality of type columns, including a plurality of pumps, each pump comprising a plunger working within a bore in a pump frame, means for

15 driving said pumps, an ink reservoir in which said pumps are seated and having a support on which said pumps are bodily slideable from a working position to an inspection position and means for securing the pumps in working position.

4. In a rotary printing press having means for supplying and conveying ink to each of a plurality of type columns, including a plurality of pumps, each pump comprising a pump frame, a plurality of plungers each working in a bore in the pump frame, a driven actuating frame for the plungers, an ink reservoir accommodating the pump frames in working and inspection positions and in which the pumps are seated and a support on which the pump frames are slideable bodily from one position to another.

30 5. In a rotary printing press having means for supplying and conveying ink to each of a plurality of type columns, including a plurality of pumps, each pump comprising a pump frame, a plurality of plungers each working in a bore in the pump frame, a driven actuating frame for the plungers, an ink reservoir accommodating the pump frames in working and inspection positions, in which the pumps are seated and a support on which the pump frames are slideable bodily from one position to another and means normally preventing movement of the pumps from one of said positions to the other.
